UNITED STATES PATENT OFFICE.

FRANK CLAUS, OF PHILADELPHIA, PENNSYLVANIA.

CLUTCH.

SPECIFICATION forming part of Letters Patent No. 722,492, dated March 10, 1903.

Original application filed January 21, 1902, Serial No. 90,637. Divided and this application filed May 28, 1902. Serial No. 109,380. (No model.)

To all whom it may concern:

Be it known that I, FRANK CLAUS, a subject of the Emperor of Germany, residing at Philadelphia, in the county of Philadelphia and State of Pennsylvania, have invented certain new and useful Improvements in Clutches, of which the following is a specification.

My invention relates to improvements in clutches, and is more particularly designed for use in connection with power-transmitting devices—such, for instance, as that type shown and described in my pending application, filed January 21, 1902, Serial No. 90,637, from which this application has been divided. It will be understood, however, that the invention herein described is not necessarily limited to devices of the particular type above mentioned, as the same may be employed for the purpose of transmitting motion either from reciprocating or rotary prime movers, as the case may require.

In illustrating the application of my invention I have shown the same applied to a device for transmitting a reciprocating motion into a rotary motion, the same being the device above referred to as forming the subject-matter of a prior invention.

Referring to the accompanying drawings, Figure 1 illustrates a plan view of a power-transmitting device employing my improved clutches. Fig. 2 is a front elevation of the same. Fig. 3 represents a vertical section of one of the clutches, taken on a line 3 3 of Fig. 4. Fig. 4 illustrates a horizontal section of the clutch, taken on line 4 4 of Fig. 3. Fig. 5 shows a detached perspective of a portion of the split ring and toggle-levers, together with a portion of the sliding bar for operating the toggles; and Figs. 6 and 7 illustrate diagrammatic views of the toggle-levers in different positions.

In order to illustrate the manner in which the clutches forming the subject-matter of this invention are used, I have shown in connection therewith the mechanical devices of the pending application above referred to and shall describe their use in connection with such mechanism.

Referring to the reference-letters of the drawings, A represents a reciprocating bar

which may be connected to any reciprocating prime mover—such, for instance, as the piston of a steam-engine or other reciprocating motive power. This bar is provided above and below with racks A' and A'', which engage pinions B' and B'', loosely supported upon shafts B¹¹ and B¹². Each of these pinions is provided with a hub b, through which passes a sliding bar C, which is united to a grooved collar D, loosely supported upon the shaft supporting the pinions. The collar D is operated by a lever E, having a bifurcated end inclosing the collar and pins e e adapted to the groove thereof. The lever E is fulcrumed at E' and is connected to a notched operating-plate E², provided with an operating finger-piece E³. The plate E² is provided with three notches e', e'', and e³, which are caused to engage the edge of a plate F to hold the lever E in position by means of a spiral spring S. The lower pinion B'', which is loosely mounted on a shaft B¹², has a similarly-arranged collar D, and the connecting parts are identical with those just described and are indicated by similar letters of reference.

In the rear of the pinions B' and B'' are cup-shaped disks G G, each being secured to its respective shaft by means of set-screws g g.

The shafts B¹¹ and B¹² are provided, respectively, with gear-wheels H and H', which engage a broad pinion I, mounted upon a shaft J, provided with a fly-wheel K.

Arranged between the pinion B' and the disk G and between the pinion B'' and lower disk G is the clutch mechanism by which the pinions may be brought into engagement with the disks to operate them in either direction, or, if desired, by moving the levers E to the proper position one or both of the clutches may be thrown out of action. As both of the clutches are identical in construction, a description of one will suffice for the other, and similar letters of reference will be employed to designate similar parts in both cases.

The hub b of each of the pinions is slotted at b' to receive the sliding bar C, which is slightly concave on its upper surface, as shown at c, to permit the lever C¹² to pass from one position to the other without distending

the ring G'. The sliding bar is provided near its end with an inclined slot C' to receive a pin C², which is projected from a lever C¹², hinged to toggle-levers C¹³ and C¹⁴.

- 5 Closely engaging the inner wall of the cupped disk G is a split ring G', which has rounded ends adapted to fit concave-surface-forming sockets in the toggle-levers C¹³ and C¹⁴. The toggle-levers are spread out, and 10 the ends of the split ring are caused to embrace the inner wall of the cupped disk by means of an elliptic spring S', which is held by a support c¹² on the hub b and bears against a cross-piece c¹³, arranged upon the pin c¹⁴, 15 which connects the levers C¹², C¹³, and C¹⁴.

When the machine is in operation, each of the levers E is operated so that the notch e² is in engagement with the plate F, as shown in Fig. 1, and then the clutches are thrown out 20 of action. If, however, the lever E be moved so that the notch e³ is in engagement with the plate F, then the levers C¹², C¹³, and C¹⁴ will assume the position shown in the diagram Fig. 5, and a movement of the bar A 25 will cause the rotatable parts to move in the direction indicated by the full arrows shown in Fig. 1. If the lever E be shifted so that the notch e⁴ is in engagement with the plate F, the levers C¹², C¹³, and C¹⁴ will assume the position 30 shown in the diagram Fig. 6, and the rotatable parts of the device by a movement of the bar A will turn in the direction indicated by the dotted arrows in Fig. 1.

Having described my invention, what I 35 claim, and desire to secure by Letters Patent, is—

1. A clutch for power-transmitting devices comprising a disk fixedly secured to a shaft, and a hub loose upon the shaft, a slideable 40 bar journaled in the hub, provided with an inclined slot, a split ring engaging the inner wall of the disk, toggle-levers, engaging the ends of the ring, a lever for operating the toggles, one end of which is guided in the inclined slot, and means for operating the slideable bar to cause the toggles to bind with one or the other ends of the ring, substantially as specified.

2. A reversible clutch for power-transmitting devices, comprising a cup-shaped disk fixedly secured to a shaft, a hub loosely mounted upon the shaft, a movable bar journaled in the hub, provided at one end with an inclined slot, a split ring arranged within the 50 disk, toggle-levers engaging the ends of the ring, a lever pivoted centrally to the toggle-levers and having a pin engaging the slotted

end of the movable bar and means for operating said bar, substantially as specified.

3. A clutch comprising a loose member and 60 a tight member mounted upon a shaft, a movable bar journaled in the loose member and having in one end an inclined slot or guide-way, a split ring adapted to engage the inner surface of the tight member, toggle-levers 65 engaging the ends of the ring and a lever pivoted to the toggles, and operated by a slot in the sliding bar, substantially as specified.

4. A clutch for power-transmitting devices, comprising a cup-shaped disk, a split ring 70 adapted to engage the inner wall thereof, a shaft fixedly secured to disk, a hub loosely journaled upon the shaft, a slideable plate guided in said hub and provided with an inclined slot, a lever provided with a pin adapted 75 to engage the slot, toggle-levers hinged to said lever at their inner ends and bearing against the ends of the ring and means to operate the sliding plate, substantially as specified.

5. A clutch for power-transmitting devices comprising a flanged disk, a split ring engaging the inner wall thereof, a shaft fixedly secured thereto, a loosely-journaled member or hub, a concave sliding plate guided in said 85 hub, provided with an inclined slot, a lever provided with a pin adapted to the inclined slot, toggle-levers hinged to the above-mentioned lever and having bearings in the ends of the split ring, a spring adapted to spread 90 the toggle-levers, and means to operate the sliding plate, substantially as specified.

6. A reversible clutch comprising in combination a cup-shaped disk, a split ring engaging the inner wall of the disk, a shaft fixedly secured to the disk, a hub loosely journaled upon said shaft, a curved slideable plate guided in said hub provided at one of its ends with an inclined slot, and at the opposite end with a grooved collar surrounding the shaft, 100 a lever provided with a pin adapted to said slot, toggle-levers hinged to the above-mentioned levers, having curved bearings in the ends of the split ring, a spring adapted to spread the toggle-levers and an operating- 105 lever having bifurcated ends engaging the groove of said collar, substantially as specified.

In testimony whereof I affix my signature in presence of two witnesses.

FRANK CLAUS.
